UNITED STATES PATENT OFFICE.

PETER COCKER, OF PHILADELPHIA, PENNSYLVANIA, ASSIGNOR OF ONE-HALF TO THOMAS DOLAN, R. WILLIAMS, JR., CHARLES H. SALMON, AND JOSEPH P. TRUITT, ALL OF SAME PLACE.

CUTTING ATTACHMENT FOR LOOMS.

SPECIFICATION forming part of Letters Patent No. 361,929, dated April 26, 1887.

Application filed October 25, 1886. Serial No. 217,131. (No model.)

To all whom it may concern:

Be it known that I, PETER COCKER, a citizen of the United States, residing in Philadelphia, Pennsylvania, have invented a certain 5 Improved Cutting Attachment for Looms, of which the following is a specification.

The object of my invention is to provide simple means whereby the fabric woven on a loom can, as fast as it is woven, be cut into as 10 many widths as desired, thereby dispensing with the necessity of cutting the fabric on a separate machine.

In the accompanying drawings, Figure 1 is a view, partly in section and partly in elevation, of part of a loom, showing the breast-beam and the lathe with my improved attachment. Fig. 2 is a plan view of the device, showing part of the breast-beam and lathe. Fig. 3 is a sectional view, partly in elevation, on the 15 line 1 2, Fig. 2; and Figs. 4, 5, and 6, views illustrating modifications.

A is part of the frame of the loom; B, the lathe pivoted at b to the frame and having the usual reed, c, and shuttle-race E, D being the 20 breast-beam of the loom, d the cloth-roll, and x the cloth.

Secured to the top of the breast-beam D, in the present instance by screws f f, is a plate, F, forked at its outer end, and enlarged for 25 the reception of a spindle, g, on which rotates a cutting-wheel, G, of hardened metal, the retaining-screws f f being adapted to slots h in the plate F, so that said plate can be adjusted, as required.

Secured to the lathe E is a bracket, I; the 30 portion i of which is so adjusted in respect to the wheel G that when the lathe beats up the wheel will ride on the projection i and cut the fabric which lies in its path. The bracket I is slotted at j for the reception of the confining-screw k, so that the bracket can be adjusted up or down on the lathe, as required. 35 As the lathe beats up, the bearing-plate i passes beneath the cutter G and presses the

cloth against the same, a new portion of cloth 45 being presented on each beat, so that the cloth is severed longitudinally as fast as it is woven. The bearing-plate i is preferably of such an elastic character that it can yield when subjected to the pressure of the cutter. 50

If desired, a knife fixed as shown in Fig. 4 may be used in place of the rotary cutter, or the cutter may be on the bracket I and the bearing-plate i on the plate F, as shown in Fig. 5, without departing from my invention, 55 and it will be understood that more than one cutter may be used. For instance, where a loom is weaving a series of strips of braid or trimming side by side, the cutters can be duplicated to accord with the number of strips to 60 be made. In some cases the plate F can be carried by a bar, F', above the breast-beam, as shown in Fig. 6.

I claim as my invention—

1. The combination, in a loom, of the lathe, 65 the breast-beam, a cutter carried by one of said parts, and a bearing-plate carried by the other part and serving to press the fabric against the cutter as the lathe beats up, all substantially as set forth.

2. The combination of the lathe, the breast-beam, the cutter, and the elastic bearing-plate for pressing the fabric against the edge of the cutter, all substantially as specified.

3. The combination of the breast-beam and 75 a plate carried thereby and having a rotary cutter with the lathe having a bracket forming a bearing plate for the fabric and serving to press the latter against the rotary cutter as the lathe beats up, all substantially as specified.

In testimony whereof I have signed my name to this specification in the presence of two subscribing witnesses.

PETER COCKER.
